W. E. SCHWARZMANN,
HOUSING FOR MECHANICAL INTERRUPTERS,
APPLICATION FILED FEB. 7, 1919.

1,335,130.

Patented Mar. 30, 1920.

UNITED STATES PATENT OFFICE.

WOLFGANG ERNEST SCHWARZMANN, OF SPRINGFIELD, MASSACHUSETTS, ASSIGNEE TO
AMERICAN BOSCH MAGNETO CORPORATION, OF NEW YORK, N. Y., A CORPORATION
OF NEW YORK.

HOUSING FOR MECHANICAL INTERRUPTERS.

1,335,130.

Specification of Letters Patent. Patented Mar. 30, 1920.

Application filed February 7, 1919. Serial No. 275,633.

To all whom it may concern:

Be it known that I, WOLFGANG E. SCHWARZMANN, a citizen of the United States, residing at 51 Bellclaire avenue, 5 Long Meadow, Springfield, in the county of Hampden, State of Massachusetts, U. S. A., have invented certain new and useful Improvements in Housings for Mechanical Interrupters; and I do hereby declare the following to be a full, clear, and exact description of the invention, such as will enable others skilled in the art to which it appertains to make and use the same.

The present invention relates to housings 15 for mechanical interrupters of magnetos or other ignition apparatus for internal combustion engines, and particularly to such, housings as carry the interrupter cams in coöperation with the rotatable interrupter contacts. In housings of this kind it was customary heretofore to have a different housing for each direction of the rotation of the interrupter, and also for fixed and variable ignition, thereby increasing the cost of 20 the manufacture and the amount of supply parts and materials required in practice.

The primary object of the invention is to provide a universal housing which may at will be used for both directions of rotation 30 of the interrupter, and also for fixed or variable ignition in either direction of rotation. Accordingly the housing comprises a member fixed to the ignition apparatus and carrying one locking element in any one of 35 several positions and a cam ring carrying a second locking element coöperative with the first to provide therewith the fixed or variable ignition in the direction of rotation desired. In the specific embodiment herein- 40 after described, an end plate of the ignition apparatus is provided with a plurality of seats adapted to accommodate a pin, and the cam ring has a plurality of slots into 45 relations of the locking elements, the cam ring is held against turning to provide fixed ignition, and in other relations the cam ring may be turned within limits to provide variable ignition.

50 In addition to the foregoing, it is also desirable to provide for different positions of the timing arm connected to the interrupter housing, because different engine builders require that the timing arm be on 55 different sides of the housing, or at certain

points therebetween, in order that the connecting rod between the timing arm and the spark adjusting lever may be most conveniently arranged.

Another object of the invention is to provide, in association with the universal housing, an arrangement whereby the timing arm may be brought to any position on either side of the housing, to suit the specific requirements of the engine builders, notwithstanding that the housing is adapted for fixed or variable ignition in both directions of rotation. To do this, I provide the timing arm with a ring adapted to interlock with the cam ring in substantially any angular position desired, so that the arm may extend on either side of the cam ring or at any point therebetween when the cam is set for fixed or variable ignition in either direction of rotation. In the specific embodiment hereinafter described, the outer surface of the cam ring is toothed and the inner surface of the timing ring also is toothed, so that the teeth thereof may be intermeshed when the timing arm is in substantially any angular position on the cam ring.

In the accompanying drawings illustrating the preferred embodiment of the invention on application, as an example, to a bipolar magneto, Figure 1 is an elevation of the rear end of the magneto with the cap removed; Figs. 2 is a front elevation of the timing ring and arm; Fig. 3 is a section on line 3—3 of Fig. 2; Fig. 4 is a side view of the cam ring; Fig. 5 is a front view of the cam ring; Fig. 6 is a front view of the end plate of the magneto; and Figs. 7 to 10 show the magneto with the parts set for fixed and variable ignition in both directions of rotation.

The magneto, 1, has an end plate 2 provided with an annular flange 3 and the screw threaded holes 4, 5 and 6 adapted to receive and seat a pin 7. The cam ring 8 fits over the flange 3 to turn thereon and has in its rear peripheral edge a short slot 9 and a long slot 10 into which the pin 7 may enter. The cam ring carries the cams 11 and 12 coöperating with the fiber block 13 of the deflectable lever 14. That lever, 105 carrying the interrupter contact 15 in coöperation with the interrupter contact 16, is rotatable with the interrupter plate 17 on the end of the armature shaft in the well known way.

The outer periphery of the cam ring is toothed at 18, and the inner surface 19 of the timing ring 20 is toothed also, so that when the timing ring is contracted around the cam ring by the screw, 21, the teeth are intermeshed. In this way the timing arm 22 may be fastened in any angular position on the cam ring to suit the requirements of the engine builder. When the timing ring 10 is intermeshed with the cam ring, the adjusting pull on the spark lever is distributed around the periphery of the cam ring with the result that the cam ring does not bind in turning on the flange 3 of the end plate, 15 no matter what angular position the timing arm may have.

The coöperative interrupter contacts 15, 16 should be separated in the period of maximum generation of the magneto, and 20 thus the fiber block 13 should engage the cam 11 or 12 to deflect the lever 14 in that period. To do this, the cam ring 8 must have a different angular position for each 25 direction of rotation to compensate for the angular extent of the fiber block, whether the ignition is fixed or variable. Fig. 7 shows the arrangement of the parts for fixed ignition in a clockwise direction of rotation of the interrupter. The pin 7 is seated in 30 the hole 5 and projects into the short slot 9, so that the cam ring is fixed in that position. In Fig. 8 the pin 7 is seated in the hole 4 and projects in the short slot 9 for fixed 35 ignition in anticlockwise direction. In Fig. 9 the pin 7 is seated in the hole 5 and extends into the long slot 10 for variable ignition in clockwise direction. In Fig. 10 the pin 7 is seated in the hole 6 and extends into 40 the long slot 10 for variable ignition in anticlockwise direction.

Thus by providing a plurality of seats for the pin 7 and a plurality of slots into which the pin may enter, the cam ring may be fixed in position in the angular position required 45 for fixed ignition in either direction of rotation, or for variable ignition in either direction of rotation. Furthermore the timing arm may have any angular relation with respect to the cam ring for fixed or variable 50 ignition in either direction of rotation. In this way all the requirements of the engine builder are met, and a single or universal housing provides for fixed or variable ignition in either direction of rotation.

Having thus described my invention what I claim is:

1. In an interrupter housing for ignition

apparatus, a member fixed to the ignition apparatus and having a plurality of seats, a locking element adapted to be mounted on 60 any one of said seats, and a cam ring carrying a locking element coöperative with the first when mounted on any one of said seats; substantially as and for the purpose described. 65

2. In an interrupter housing for ignition apparatus, a member fixed to the ignition apparatus and having a plurality of seats, a pin adapted to be mounted on any one of said seats, and a cam ring having a slot 70 for receiving the pin when mounted on said seats; substantially as and for the purpose described.

3. In an interrupter housing for ignition apparatus, a member fixed to the ignition 75 apparatus and having a plurality of seats, a pin adapted to be mounted on any one of said seats, and a cam ring having a plurality of slots into which the pin may enter when mounted on said seats; substantially as and for the purpose described. 80

4. In an interrupter housing for ignition apparatus, a member fixed to the ignition apparatus and having a plurality of seats, a pin adapted to be mounted on any one of 85 said seats, and a cam ring having short and long slots into which the pin may enter when mounted on said seats; substantially as and for the purpose described.

5. In an interrupter housing for ignition 90 apparatus, a member fixed to the ignition apparatus and having a plurality of seats, a locking element adapted to be mounted on any one of said seats, a cam ring carrying a locking element coöperative with the first 95 when mounted on any one of said seats and having wedge teeth on its periphery, and a timing ring having wedge teeth adapted to engage the wedge teeth on the cam ring.

6. In an interrupter housing for ignition 100 apparatus, a member fixed to the ignition apparatus and having a plurality of seats, a locking element adapted to be mounted on any one of said seats, a cam ring carrying a locking element coöperative with the first 105 when mounted on any one of said seats and having its outer surface toothed, a timing ring having its inner surface toothed to engage the toothed surface of the cam ring, and means for contracting and expanding 110 the timing ring around the cam ring.

In testimony whereof I affix my signature.

WOLFGANG ERNEST SCHWARZMANN.
